(57) **CLAIM**

The ornamental design for a bag dispensing clip, as shown and described.

DESCRIPTION

FIG. 1 is a perspective view of a bag dispensing clip, showing our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof;

FIG. 7 is a side elevational view thereof, opposite that shown in FIG. 6; and,

FIG. 8 is a perspective view of the bag dispensing clip of FIG. 1 shown in its environment.

The broken lines shown herein are for illustrative purposes only and form no part of the claimed design.

1 Claim, 5 Drawing Sheets

FIG. 1.

FIG. 2.

FIG. 3.

FIG. 4.

FIG. 5.

FIG. 6.

FIG. 7.
